CHRISTIAN REINHART, OF NEW HAVEN, CONNECTICUT.

Letters Patent No. 79,003, dated June 16, 1868.

IMPROVEMENT IN ESCAPEMENTS FOR CLOCKS.

The Schedule referred to in these Letters Patent and making part of the same.

TO ALL WHOM IT MAY CONCERN:

Be it known that I, CHRISTIAN REINHART, of the city and county of New Haven, in the State of Connecticut, have invented certain new and useful Improvements in Escapements for Marine and other Clocks and Time-Pieces; and the following is a full, clear, and exact description of the same, reference being had to the accompanying drawings, making a part of this specification, in which—

Figure 1 represents a top view of the balance-wheel, forked lever, pin-lever, and double-toothed crown-wheel in their relative positions.

Figure 2 shows a side elevation, with a view of the escapement-shaft and pallets, and frame for hanging and adjusting the same to the crown-wheel.

Figure 3 shows a detached view of the same in perspective, enlarged.

Figure 4 is an enlarged view of the lever, pin-lever, and broken-off section of the crown-wheel.

Figure 5 is the double-toothed wheel and check-plate or top pallets.

Figure 6 shows an edge view of the same parts as shown in fig. 4.

Figure 7 is a side view of fig. 5.

Figures 8 and 9 show the escapement-collets.

To enable others to make and use my invention, I will describe it more fully, referring to the drawings, and to the letters marked thereon.

The object of my invention is to get a durable and efficient escapement for marine clocks and other time-pieces; and it consists in the construction of the double-toothed crown-wheel, the collet or plate-verge, and stop-pallet, on a vertical shaft, the short forked lever, and pin-arm, as arranged and combined with a balance-wheel, hair-spring, and regulator.

I make the escapement or crown-wheel A double, it having two rims; on which the teeth $\alpha\alpha\alpha$, being very sharp pointed, incline to each face, so as to leave a space, b, between the points $\alpha\alpha\alpha$. The collet B, which forms the verge proper of this escapement, is made of steel, and fitted on to a vertical shaft, C, to which the forked lever D is secured, so as to oscillate the required distance to allow the points of the teeth $\alpha\alpha\alpha$ to escape alternately right and left through the inclined spaces or notches, e e, in the collet B.

On the vertical shaft C, a short distance above the collet or verge B, I place the stop-plate E, which is also made of steel, and is provided with one open space, f, through which the teeth $\alpha\alpha\alpha$ of the crown-wheel A escape as the lever D vibrates. The pallets i i, on each side of the opening f in the stop-plate or collet E, check the movement of the crown-wheel. At the same time, the motion of the lever being reversed, the inclines j j, on the collet-verge B, give momentum to the lever, so that the fork d d, acting on the pin h, in the arm k, which is connected with the shaft G, on which the balance-wheel H is hung, gives a lively vibratory movement to the balance-wheel H and shaft, on which the pin-lever k is secured, so that they nearly describe a circle at each beat of the escapement, the distance the forked lever is allowed to move being controlled by the width of the opening m, in the arm of the lever D, and the pin or stud n for the lever to strike against.

The balance-wheel, shaft, lever, and verge-collets, with the shaft on which they are placed, are all arranged and supported in a frame, F, independent of the plates I I, in which the clock-movement is arranged, so that it can be placed in any position to come in contact with the double-toothed crown-wheel that it may be desirable to have it placed in, so that the movement for marine clocks, or other time-pieces, can be arranged in the most compact manner, and occupy but very little space.

My improved escapement may be applied to clocks or time-pieces of any form or of any dimensions, and for the accuracy of its performance and certainty of action cannot be excelled by any escapement that has yet come to my knowledge.

The advantages of my improvement are, that the clock measures time with greater accuracy than those with the ordinary rack or detached-lever escapements, it having a greater force of movement, will run with much less power of spring than other eight, fourteen, or thirty-day clocks, and consequently will be more durable, less liable to wear in its boxes, and is much easier wound up.

It will readily be seen that the advantages above enumerated are no small desideratum in a marine clock or other time-piece, and it is confidently believed that the escapement-movements, constructed as above described, (and jewelled,) as I propose to make them, will last, to keep correct time, a century or more, or as long as the clock-movement is kept together.

Having thus fully described my invention, what I claim as new, and desire to secure by Letters Patent, is—

1. The double-tooth crown-wheel A, as constructed, in combination with the verge-collet B and stop-collet E, operating substantially as and for the purposes herein specified.

2. The verge-collet B, stop-plate E, as constructed and arranged, in combination with the forked lever D, pin h, arm k, and balance-wheel H, as set forth.

3. The forked lever D, with its open space m, stop-pin or stud n, when the lever is balanced on the verge-shaft C, so as to distance the motion of the collet B and stop-plate E, to allow the points a a to escape through the incline openings e e and opening f, as herein described.

In testimony whereof, I hereunto subscribe my name in the presence of—

CHRISTIAN REINHART.
